DESIGN FOR A COMBINATION PROTRACTOR OR SIMILAR ARTICLE

Andrew W. Colmery, Canton, Ohio

Application November 19, 1943, Serial No. 111,729

Term of patent 14 years

To all whom it may concern:

Be it known that I, Andrew W. Colmery, a citizen of the United States, residing at Canton, in the county of Stark and State of Ohio, have invented a new, original, and ornamental Design for a Combination Protractor or Similar Article, of which the following is a specification, reference being had to the accompanying drawing, forming part thereof.

Figure 1 is a plan view of the combination protractor showing my new design;

Fig. 2 is a side elevation thereof; and

Fig. 3 is an end view thereof.

I claim:

The ornamental design for a combination protractor or similar article, as shown,

ANDREW W. COLMERY.
